UNITED STATES PATENT OFFICE

2,323,108

ROAD GRADER

Franklin E. Arndt, Galion, Ohio, assignor to The Galion Iron Works & Manufacturing Company, a corporation of Ohio

Original application November 23, 1938, Serial No. 241,979. Divided and this application April 29, 1941, Serial No. 390,953

8 Claims. (Cl. 37—156)

My invention relates to road graders, and one of its objects is the provision of improved and efficient drawbar structure for adjustably supporting a circle carrying the grader blade or moldboard.

Another object of the invention is the provision of improved and efficient mechanism for supporting a moldboard circle on a drawbar and adjusting such circle relative to the drawbar.

Other objects of the invention will appear hereinafter, the novel features and combinations being set forth in the appended claims.

In the accompanying drawings,

Figs. 1 and 2, placed end to end, show a side elevation of the road grader embodying my improvements;

Figs. 3 and 4, placed end to end, show a plan view of the road grader shown in Figs. 1 and 2, but with the moldboard shifted to a longitudinal position from the transverse position shown in Fig. 2;

Fig. 5 is an enlarged sectional plan view of the gearing for operating the circle to shift the moldboard from the transverse position shown in Fig. 2 to the longitudinal position shown in Fig. 4;

Fig. 6 is a sectional view taken on the line 6—6 of Fig. 5, looking in the direction of the arrows;

Fig. 7 is a plan view of the supplemental frame serving as a drawbar, as shown in Figs. 3 and 4 placed end to end;

Fig. 8 is a side view of the structure shown in Fig. 7 adapted to serve as a drawbar, as illustrated in Figs. 1 and 2 placed end to end; and

Fig. 9 is a sectional elevation of the front steering wheel unit, looking forward, the section being taken on the line 9—9 of Fig. 1, looking in the direction of the arrows.

This application is a division of my co-pending application S. N. 241,979, filed Nov. 23, 1938, and since issued as Patent No. 2,247,007, for a Road grader.

Referring to the road-working implement comprising a moldboard or scraper blade 109 and the structure for supporting the same, it will be seen that the supplemental frame 110 constitutes a drawbar for the moldboard 109. This supplemental frame or drawbar is a rigid structure relatively narrow and elongated throughout most of its length, particularly at its forward end portion, to facilitate its movement laterally of the narrow elongated main frame, when the moldboard is shifted from road-grading position to steep

bank-cutting position at one side of the machine. By referring to Fig. 3 of the drawings it will be seen that the forward portion of the main frame is narrower than the main portion of the drawbar, but the latter is tapered at its forward end where it is even narrower than the main frame.

While the main frame is upwardly arched to provide ample room for the drawbar and moldboard in their various positions of adjustment, the drawbar is so shaped as to have its rear end portion approximately horizontal when the moldboard is in road grading position. The intermediate portion of the drawbar is inclined upwardly and forwardly, as shown in Figs. 1 and 2 placed end to end. The forward end portion of the drawbar slopes upwardly and forwardly more gradually than the intermediate portion and has its upper portion at 111 approximately horizontal so as to increase the space between the front end of the drawbar and the beams 40, 40 of the main frame which slopes downwardly and forwardly at its forward end, as viewed in Fig. 1. It should be understood that the main frame and drawbar are thus specially shaped to facilitate movement of the moldboard to steep bank-cutting position. These special shapes of the frames are particularly desirable when the moldboard is to be shifted to an upright bank-cutting position.

The drawbar, as shown in Figs. 7 and 8, comprises spaced-apart angles 112, 112 connected by the transverse bracing tubes 113, 114, the ends of which are welded to the angles 112, 112. Welded between the forward ends of the angles 112, 112 is a longitudinally extending tubular socket 115. As shown in Fig. 1, an I-bolt 116 is adapted to be swiveled to the front end of the drawbar having its screw-threaded rod 117 extended through the socket 115 and secured in place by the nut 118. A horizontal U-bolt 119 extends through the I-bolt 116, as shown in Fig. 1, and this U-bolt extends through openings in the laterally extending brackets 120, 120 and is held rigidly connected to the vertical post 45 by means of the nuts 121. The rear side of the post 45 has a semi-circular recess, as indicated at 122 in Fig. 3, for receiving the forward end of the I-bolt 116 but it should be understood that while the U-bolt 119 occupies a horizontal plane, and the I-bolt 116 occupies a vertical plane, a universal connection is afforded to the extent that the I-bolt may be moved laterally on a vertical pivot relative to the U-bolt 119 and also vertically on a hori-

zontal pivot relative to the U-bolt 119. By reason of the universal connection between the front end of the drawbar 110 and the post 45, the front end of the drawbar may be swung laterally and vertically and also rotated in either direction on the axis of the bolt 117.

To the rear ends of the heavy structural angles 112, 112 is welded the cross-piece 123 to which in turn is welded the additional cross-piece 124. Diagonal braces 125, 125 are welded at their ends to the structural angles 112 and the cross-piece 123. To the outer ends of the cross-pieces 123 and 124 are welded the longitudinally extending tubular sockets 126, 127. The socket 126 is adapted to receive the neck 128 of the spherical head 129 which is adapted to serve as the ball of the ball and socket joint at the lower end of an extensible hanger, as hereinafter fully explained. The socket 127 is adapted to receive at its ends the necks 130 and 131 of the spherical heads 132 and 133, respectively. The head 132 is adapted to serve as the ball of a ball and socket joint at the lower end of another extensible hanger at the opposite side of the machine. The head 133 is adapted to serve as the ball of a ball and socket joint for one end of the laterally shifting hydraulic motor as hereinafter fully explained. The neck 128 is held in the socket 126 by means of the bolt 134. The necks 130 and 131 are held in the socket 127 by means of the bolts 135 and 136, as shown in Fig. 7.

To the under sides of the structural angles 112, 112 and the under sides of the cross-pieces 123, 124 is welded a shallow cup-shaped bearing support 137 having a central opening 138 for receiving the king pin 139 shown in Fig. 2. The lower side of the bearing support 137 is circumferentially flanged at 140 to provide on its under side the annular bearing 141. It will thus be seen that the drawbar structure shown in Figs. 7 and 8 is well braced and reinforced in an all welded assembly including the bearing support 137.

The semi-circle 142 is preferably forged integrally with the moldboard knees 143, 143 which are connected by the diagonal braces 144, 144 to the cross-piece 145, as shown in Fig. 4. The lower or depending ends of the knees 143 are pivoted at 146 to the moldboard carrier 147 which may be adjustably connected to the knees 143 by means of the bolts 148 and perforations 149, as shown in Fig. 2.

The semi-circle 142 is reinforced by the diagonal braces 150, 150 which are secured at their rear ends to the cross-piece 145, as shown in Fig. 4. The semi-circle 142 is additionally reinforced by the structural angles 151, 151, 152, 152 and 153, as shown in Fig. 4. Within the square space enclosed by the structural angles 152, 152, 153 and the cross-piece 145, is located the wheel shaped or disc shaped bearing support 154, the cylindrical periphery of which is preferably welded to the cross-piece 145 and the structural angles 152, 152, 153. The bearing support 154, as shown in Fig. 2, is of the same diameter as the flange 140 of the bearing support 137. The upper peripheral ring portion of the bearing support 154 engages the lower peripheral portion 141 of the bearing support 137. The bearing support 137 is provided with a hub 155 concentric with the hub 156 of the lower bearing support 154. The hub 155 is rigid with the drawbar structure, and the hub 156 is rigid with the semi-circle structure, the lower end of the hub 155 being en-

gaged by the upper end of the hub 156 when the king pin 139 is in the position shown in Fig. 2. A cap plate 157 of larger diameter than the king pin 139 is secured to the lower end of the latter by means of the cap screw 158 in position to engage the lower end of the hub 156. The washer 159 engages the upper end of the hub 155 and a nut 160 locked to the upper end of the king pin 139 is relied on to hold the bearing supports 137 and 154 in mutual engagement over wide areas of bearing surfaces. That is to say, not only are the adjacent ends of the hubs 155 and 156 held in engagement with each other but the annular bearing surfaces of the circular bearing supports 137 and 154 are also held in engagement with each other.

The mechanism for rotating the semi-circle 142 together with the moldboard 109 carried thereby is power-operated under control of the operator at his station at the rear end of the machine shown in Fig. 2, and this power-operated mechanism is so arranged as to be fully operative in any position of adjustment of the moldboard, including steep bank-cutting positions. As shown in Fig. 6, annular gearing 161 is secured to the semi-circle 142 and with this annular gearing meshes a pinion 162 carried by the lower end of the shaft 163 (Fig. 5) journaled in a bearing 164 detachably bolted to the structural angles 112, 112 of the drawbar frame. For this purpose transverse perforations 165, 165 are provided in the vertical flanges of the structural angles 112, 112, as shown in Figs. 7 and 8.

As shown in the enlarged sectional elevation of Fig. 5, the housing 166 for the journal bearing 164 spans the space between the structural angles 112, 112 and is bolted thereto by means of the bolts 167, 167. Keyed to the upper end of the shaft 163 is a worm wheel 168 located in the housing 169, and this worm wheel meshes with a worm 170 which is keyed to the shaft 171 which extends longitudinally of the drawbar frame and toward the front end thereof, as shown in Fig. 2. By means of cap screws 172 a cover 173 is secured to the gear housing 169. A nut 174 locks the worm wheel 168 to the shaft 163, as shown in Fig. 5. By connection to the fitting 175, lubricant may be introduced into the housing 169 without removing the cover 173. The worm gearing 168, 170 is preferably self-locking to hold the moldboard in adjusted position on the king pin 139 relative to the drawbar frame.

The forward end of the shaft 171 is connected by means of the universal joints 176, 177 and connecting link 178 to the shaft 179, the forward end of which is connected to a spur gear rotatable on a longitudinal axis and meshing with another spur gear connected to the rearwardly extending shaft 179', the spur gearing being mounted in the housing 180 which is attached to the vertical flange of the structural angle 112 shown in Fig. 1.

By placing Figs. 1 and 2 end to end it will be seen that the rearwardly extending shaft 179' is connected by means of the universal joints 181, 182 and intermediate connecting link 183 to the horizontal rearwardly extending shaft 184. The link 183 is extensible in length in that it comprises a tubular section 185 having a socket square in cross-section into which fits the rod 186 also square in cross-section.

The rear end of the horizontal shaft 184 is connected by means of a universal joint 187 to a shaft which is journaled in the bearing 189 in the front side of the housing 190, as shown

in Fig. 2. Within the housing 190 is located manually controlled power-operated reversing mechanism for effecting rotation of the moldboard in opposite directions on the axis of the king pin 139. For this purpose, an internal combustion engine 191 is mounted on the main frame adjacent the operator's platform 192, as shown in Fig. 2, and connected to the operating gearing.

By means of an upwardly extending operating lever 215 which is adapted to be moved forwardly and rearwardly, the operating gearing may be actuated to effect reversal of rotation of the moldboard semi-circle operating mechanism.

When the lever 215 is moved rearwardly the moldboard is rotated on the king pin 139 in one direction and when the lever 215 is moved forwardly the moldboard is rotated in the opposite direction.

It should be noted that while the internal combustion engine 191 may be continuously operated at relatively high speed, the gearing effects such speed of rotation of the moldboard on the axis of the king pin 139 as to enable the operator to adjust the position of the moldboard relative to the drawbar with accuracy while under his observation, and this is particularly true since the main frame of the machine is open and relatively narrow adjacent the moldboard.

When the operating lever is released spring-actuated centering mechanism automatically returns the lever to neutral position, when the self-locking worm gearing is relied on to hold the moldboard in adjusted angular relation to the drawbar.

By reason of the narrow width of the front end of the main frame and the forward tapering to a narrow width of the front end of the drawbar, as shown in Fig. 3, the drawbar is free to be moved on its flexible connection between the front end of the drawbar and the post 45, to an upright plane where the moldboard is in upright bank-cutting position. This is particularly true by reason of the fact that the vertical flanges of the angle iron structures 112, 112 are spaced-apart to a no greater distance than the vertical plates of the channel iron structures 40, 40 of the main frame, as may be seen by referring to Fig. 3. Furthermore, the tapering of the vertical flanges of the angle iron structures 112, 112 at 111 (Fig. 1) enables the hangers to lift the moldboard up off the roadway and to hold the moldboard with ample clearance of the road surface while being shifted laterally to steep bank-cutting position. For all desired adjustments of the drawbar there will be no interference with the front end portion of the main frame.

When the moldboard is operating in steep bank-cutting position it may hook back of an obstruction in the bank, tending to pull the semi-circle 142 from the king pin axis 139 to the rear end of the drawbar. To assist the king pin to resist such pulling strain, a guide plate 386 may be secured by means of the bolts 387 to the bottom of the bracket 388, as shown in Fig. 2. As shown in Fig. 7, the bracket 388 may comprise the plates 389, 389 welded to the inner faces of the vertical flanges of the angle iron structures 112, 112. A cross-plate 390 is shown welded at its ends to the plates 389, 390 in vertical position to receive the bolts 387 of Fig. 2. The bracket structure 388 co-operates with the bracing tubes 113 and 114 to rigidly connect the angle iron structures 112, 112 of the drawbar frame.

The upper and lower edges of the semi-circle 142 are guided along the lower sides of the horizontal flanges of the angle iron structures 112, 112, and the lower edge of this semi-circle 142 is guided along the upper surface of the guide plate 386, as shown in Fig. 2.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a road grader, the combination with a drawbar having spaced-apart vertical flanges, of a grader blade circle pivoted to said drawbar on an upright axis, an arcuate rack on said circle, driving gearing supported by and between said vertical flanges and connected to said rack at the front end portion of said circle, direction gearing supported by said drawbar in advance of said driving gearing, a flexible connection between said driving gearing and said direction gearing, means comprising a horizontal plate suspended from said drawbar below the front end of the circle below and adjacent to said driving gearing, and means extending rearwardly from said direction gearing for actuating the latter, the construction and arrangement being such that while said driving gearing turns said circle the front end of the latter rests on said horizontal plate below and near such driving gearing.

2. As an article of manufacture, a road grader drawbar having on its bottom at its rear end two downwardly facing concentric bearings both in the same plane and surrounding a central opening adapted to receive a king pin for pivotally supporting a grader blade circle.

3. A road grader comprising the combination with a semi-circle, of supporting framework therefor having a square opening therethrough, and a circular bearing extending into said square opening and having its periphery at spaced-apart points welded to said framework at the inner sides of said square opening.

4. A road grader comprising the combination with a semi-circle, of supporting framework therefor, said framework having an opening therethrough, and a circular bearing extending into said opening and welded to the framework at the inner sides of said opening, said circular bearing having an annular bearing surface on its upper side.

5. A road grader comprising the combination with a semi-circle, of supporting framework therefor, said framework having an opening therethrough, and a circular bearing welded to said framework to occupy a position in said opening, said circular bearing having concentric annular bearing surfaces on its upper side with an upwardly facing depression between them and with an opening through the center of the circular bearing to receive a king pin.

6. A road grader comprising the combination with a semi-circle, of supporting framework within the boundary thereof, said framework having an opening therethrough with a plurality of straight sides, a circular bearing in said opening and welded to said straight sides, said circular bearing having an annular bearing surface on its upper side, and an annular rack spaced radially from said circular bearing and having

as its center the center of said circular bearing, said rack being concentric with said annular bearing surface.

7. A road grader comprising the combination with a relatively narrow drawbar, of a circle support having on its under side a downwardly facing annular bearing the diameter of which is approximately equal to the width of said drawbar, a semi-circle having an arcuate rack, supporting framework for said semi-circle, mechanism secured to said framework to afford an upwardly facing annular bearing surface adapted to engage said downwardly facing annular bearing, said annular bearings being spaced inwardly from said arcuate rack, means comprising a king pin for pivotally connecting at the centers of said annular bearings said semi-circular and said drawbar, means carried by said drawbar in advance of said semi-circle for supporting the forward portion of the latter, and means on the drawbar spaced forwardly of said annular bearings and comprising a pinion meshing with said arcuate rack for rotating the semi-circle on the king pin as a center.

8. A road grader comprising the combination with a drawbar, of a disc secured to said drawbar and having an opening in its center with a downwardly facing hub surrounding such opening and an annular bearing facing downwardly and spaced radially from said hub, a semi-circle having an arcuate rack spaced from said annular bearing and concentric therewith, a disc mounted on said semi-circle of about the same size as said first-named disc and having an opening in its center with an upwardly facing hub surrounding said last-named opening and an upwardly facing annular bearing spaced radially from said last-named hub, and means comprising a king pin extending through the openings in said discs for pivotally connecting said semi-circle to said drawbar, the construction and arrangement being such that said hubs engage each other and said annular bearings engage each other with the latter entirely separated from said arcuate rack but concentric therewith.

FRANKLIN E. ARNDT.
